(57) **CLAIM**

The ornamental design for an electrical connector as shown and described.

DESCRIPTION

FIG. 1 is a front view of an electrical connector showing our new and ornamental design according to a first embodiment;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a perspective view thereof;

FIG. 8 is a front view of an electrical connector showing our new and ornamental design according to a second embodiment;

FIG. 9 is a rear view thereof;

FIG. 10 is a left-side view thereof;

FIG. 11 is a right-side view thereof;

FIG. 12 is a top view thereof;

FIG. 13 is a bottom view thereof;

FIG. 14 is a perspective view thereof;

FIG. 15 is a front view of an electrical connector showing our new and ornamental design according to a third embodiment;

FIG. 16 is a rear view thereof;

FIG. 17 is a left-side view thereof;

FIG. 18 is a right-side view thereof;

FIG. 19 is a top view thereof;

FIG. 20 is a bottom view thereof; and,

FIG. 21 is a perspective view thereof.

(Continued)

The broken lines in the drawings depict portions of the electrical connector that form no part of the claimed design.

1 Claim, 12 Drawing Sheets
